UNITED STATES PATENT OFFICE.

THOMAS A. DE VILBISS, OF TOLEDO, OHIO, ASSIGNOR TO THE DE VILBISS MANUFACTURING COMPANY, OF TOLEDO, OHIO, A CORPORATION OF OHIO.

DESIGN FOR A DROPPER BOTTLE.

Application filed October 24, 1921. Serial No. 510,148. Term of patent 3½ years.

To all whom it may concern:

Be it known that I, THOMAS A. DE VILBISS, a citizen of the United States, residing at Toledo, in the county of Lucas and State of Ohio, have invented a new, original, and ornamental Design for a Dropper Bottle, of which the following is a specification, reference being had to the accompanying drawing, forming a part thereof.

In the drawing Fig. 1 is an enlarged side elevation of a dropper bottle showing my new design, and Fig. 2 is an enlarged edge view thereof.

The dropper bottle embodying my new design is intended particularly as a perfume container and dropper for carrying in ladies' purses and small hand bags.

I claim:

The ornamental design for a dropper bottle, substantially as shown.

THOMAS A. DE VILBISS.
